PULLING IMPLEMENT

Leo Haubert, Tulsa, Okla.

Application August 14, 1953, Serial No. 374,207

9 Claims. (Cl. 254—1)

This invention relates to pulling implements and in general aims to provide improvements in the construction of the pulling implement disclosed in my Patent No. 2,639,890 dated May 26, 1953, to which reference should be made.

The principal objects of the present invention are:

(1) To provide an attachment for lift jacks which forms the base and support for the lift jack and cooperates therewith to form a pulling implement or tool;

(2) To provide a pulling implement or tool wherein a lift jack is used which can be operated in several positions;

(3) To provide a chain pulling implement which will permit close adjustment of the chain to be pulled;

(4) To provide a chain-holding pin that cannot accidentally disengage;

(5) To provide a pulling implement wherein the pulling chain is guided through a chain guide, or around a chain sheave, or may operate outside of the chain guide or chain sheave.

To those skilled in the art, other objects of the invention will be understood from the following description of several forms of the attachment, taken in connection with the accompanying drawings forming a part of this specification.

In the accompanying drawings—

Fig. 1 is a side elevation of an assembly consisting of a conventional lift jack and an attachment for the base of the lift jack, said attachment embodying the invention;

Fig. 2 is a top plan view of the base attachment per se omitting part of the chain which secures the locking pin;

Fig. 3 is a longitudinal vertical section through the base attachment of Fig. 2;

Fig. 4 is a top plan view of a different form of base attachment;

Fig. 5 is a side elevation of the base attachment of Fig. 4;

Fig. 6 is a fragmentary side elevation showing another form of base attachment adapted to mount two chain sheaves for two chains, only one sheave however being shown; and

Fig. 7 is a section on line 7—7 of Fig. 3.

Referring particularly to the drawings, and first to Figs. 1, 2 and 3, a lift jack 10 (which is representative of any portable lift jack) has its lower end received in a socket 11 provided on the upper face of a massive base member 12 which is so designed as to provide a stable support for the jack. Base member 12, it will be understood, takes the place of the usual foot or base which is normally an integral part of the jack, the latter being modified to this extent. If preferred, the jack need not be modified at all as its foot or base may fit upon a seat designed to receive it and provided on top of base member 12, as is disclosed in my Patent No. 2,639,890. Jack 10 has the usual toothed rack bar 13, rack bar head 14, a pivoted handle socket 15, a handle or lever

2

16 (only part of which is shown) fitting in socket 15, a trip latch 17, and a rack bar toe lift 18. It will be clear that if the trip latch 17 is in the proper position, vertical oscillation of lever 16 will cause the rack bar 13 and the toe lift 18 to rise one tooth at a time, while reversing the position of the trip latch will release a pawl (not shown) and permit the rack bar to descend in the jack housing 19. In lieu of such a lift jack, other types of lift jacks may be employed with the attachment 10 of the invention with equally good results, as will be clear from the description to follow. A bore or bores 20 are preferably provided in the walls of socket 11 to permit a set screw or screws 21 to be passed through said bore to contact the lower end of lift jack 10 when it is in socket 11, thereby to lock the lift jack upon base member 12; or a bolt may be passed through the jack and socket to secure these parts together, as will be understood without illustration; or the jack-locking means of the aforesaid patent may be used to hold the jack immovably upon the base, yet permit separation of the parts whenever desired. The lower end of the lift jack housing 19 is square and is received in a square socket 11 (Fig. 2); this construction and arrangement of parts permits the lift jack to be operated in the position shown, or to be turned about its axis 90° or 180° relative to the base member 12 and still fit the socket. The socket is deep enough to prevent tilting of the jack.

In lieu of a lift jack of the type employing a stationary housing, like housing 19, and a traveling rack bar, like rack bar 13, the invention may be employed with the type of pulling implement which is in commercial use for straightening utility poles and which includes a stationary rack bar along which a housing travels tooth-by-tooth as the lever is oscillated.

Secured to the base 12 by means of a chain 25 is a chain-locking pin 26. A hold-down chain guide 27 is integral with base 12 and has a curved chain-guiding surface 28. The chain-guiding surface 28 is really the top of a groove, as seen in Fig. 2, which receives the vertical links of the chain 30; this groove is partly horizontal and partly inclined upwardly, as shown in Fig. 3. A pair of spaced co-operating chain guiding fins 29 are also integral with base 12 and have upcurved ends 29a, Fig. 3. Chain 30 to be pulled by the lift jack has one end (or a link intermediate its ends) engaging a slot in the rack bar toe lift 18 (as will be understood from the aforesaid patent, hence is not illustrated). Chain 30 passes down between the curved face 28 and the pair of chain-guiding pins 29, with those of its links which are in a vertical plane passing between the spaced fins 29, while those of its links which lie in a plane at right angles to the vertical pass or slide over the top surfaces of fins 29. Fig. 3 shows chain 30 slackened or not under tension; if chain 30 is tensioned, the upper edges of those of its links which are in the vertical plane 55 will contact and slide along the curved face 28. A pair of aligned bores 31 extend horizontally through base 12; the axis of bores 31 is located above the fins 29 and below the chain-guiding slot 28. Bores 31 are not round in cross section but are elongated, or generally elliptical, with the major axis of each bore at an angle of about 30° relative to the horizontal. Chainlocking pin 26 is adapted to pass through bores 31 and through one of the vertical links of chain 30 to lock the chain to the base 12, as when it is desired to disengage the chain from the rack bar toe lift 18 and yet hold the chain tensioned. Chain-locking pin 26 has a projection or collar 32 fixed to the shank of the pin at a point intermediate its ends which fits inside of bore 31 when the pin is in locking position to prevent the pin from being accidentally disengaged, as will be understood from Fig. 2.

With chain 30 located as shown in Figs. 1 and 3, it will exert a horizontal pull as the lift jack rack bar is

moved upwardly. However, if the pull of the chain must be at an angle or over round objects, chain 30 is removed from the guides 27, 29. Then of course bores 31 are not used to receive the chain-locking pin 26. Instead, a pair of slots 33, 34 are provided between the chain guide 27 and socket 11, said slots being on opposite sides of the base 12 and including substantially vertical faces or edges 33a, 34a adapted to be contacted by locking pin 26 when the latter is inserted in the opening of one of the chain links. Now the vertical slot edges 33a, 34a are so positioned relative to bores 31, that is the spacing is such, that when chain 30 is under tension from the rack bar of the lift jack, locking pin 26 may be passed through a selected one of the vertical links (sometimes called the "edgewise" links), either the link between bores 31 or the one adjacent slots 33, 34. The operator can select whichever link is closest to the position of registry with the locking pin, and thus the chain will scarcely be slackened at all when it is disengaged from the rack bar and all of its tension is transmitted through the locking pin to the base member 12. Thus a close adjustment of chain 30 is possible. This close adjustment is made even closer by the shape and position of bores 31 which make it possible for the locking pin to engage an end of the link selected, instead of being passed through the selected link to hold the chain. It will be clear from Fig. 3 that the lower end (the left hand end) of the chain link through which the locking pin is shown as passing might be in contact with the locking pin if the chain were pulled up a distance equal to about half the overall length of a single link, and if this contact took place, the chain would be locked by the locking pin as effectively as if the pin were passed through a link as illustrated. Also, Fig. 3 will make it apparent that if the chain were pulled up about one-fourth of the over-all length of one link, the locking pin when laid across the opening between the two slots 33, 34 will engage under the "edgewise" or vertical link at the lower end thereof to hold the chain "locked" to base 12. In other words, the chain would be held under tension and could not separate itself from base 12.

While the base 12 could be symmetrically made relative to its socket 11, that is, it could be made exactly the same on the right side of the socket as on the left (as the parts are viewed in Fig. 1), I have shown on the right side a hook 35 which is pivoted to the base by means of a bolt 36 and which has a notch 37 and a concavity or seat 38 for receiving a link of a chain 30a to anchor base 12 when the latter is subjected to the stresses imposed by the reaction from a tightened chain 30. Hook 35 is formed with an integral stop 39 which contacts a cross pin 40 fixed to base 12. The pivoted end of hook 35 is curved arcuately, as shown at 41, about pivot bolt 36 as an axis so that said hook may freely swing clockwise at the parts as viewed in Fig. 3, thus permitting the hook to be swung to release the anchoring chain hooked onto it. Counterclockwise movement of the hook is prevented by the cross pin 40.

Now referring to the form of the invention shown in Figs. 4 and 5, all like parts are identified by the same reference numerals used in Figs. 1, 2 and 3, and these like parts will not be described a second time. The form of Figs. 4 and 5 is distinguished by two advantageous features, viz., an improved anchoring means and an improved conformation of the bottom of base 12.

The improved anchoring means are two integral anchoring flanges 45 and 46, extending horizontally out from base 12a, each flange having a bore 45a or 46a through which a bolt, spike or the like may be passed to hold the base 12a rigidly to some firm support. This form of the invention is provided with three different anchoring means, viz.:

- (1) The anchor hook 35;
- (2) The anchor lock bolt 36 (which may be engaged by an anchor chain);
- (3) Flanges 45, 46.

There are times when one anchoring means will be preferred to either of the others.

The curvature 47 provided in the bottom of base 12a including flanges 45, 46, as shown in Fig. 5, is of importance especially when the pulling implement is used as a load binder, as the curvature will permit the pulling implement to fit or straddle round or irregular objects.

Fig. 6 shows a base 12b wherein a pair of rotatable chain sheaves 50 are provided, only one sheave being shown. Each chain sheave is pentagonal and has notches 51 at the angles of the pentagon for receiving the ends of a chain link which straddles or fits over the sheave, as will be understood without illustration. The sheaves will rotate as the chains meshing with them are tightened by the lift jack, and when the chains are to be secured to the base 12b, the locking pin will be inserted through bores 31 or between the slots 53, only one of the slots being shown, as both slots are alike.

Obviously a number of changes may be made in the described construction and arrangement of parts, provided such changes are within the scope of the appended claims.

What I claim as new and desire to secure by Letters Patent is:

25. 1. In combination, a lift jack; a base having a socket in which the lower end of the lift jack snugly fits so that the jack stands substantially vertically when the base is horizontal; and removable fastening means for securing the lower end of the jack within said socket; said base having guiding means for a flexible pulling element.
30. 2. In combination, a lift jack; a base having guiding means for a flexible pulling element; said base also having a socket for receiving the lower end of the lift jack; said socket and said lower end being complementarily shaped and so constructed and arranged that the lift jack may be turned on its longitudinal axis and may fit into the socket whatever the angular position of the socket.
40. 3. A base member for lift jacks having socket means on its upper face for receiving the lower end of a lift jack thereby to provide a stable support for the lift jack; said base member having a passageway for a chain extending from one end around in a curve upwardly and adjacent the socket, said passageway including chain-guiding surfaces; a cross bore intersecting said passageway; and a chain-locking pin adapted to pass into said cross bore and contact the chain in said passageway.
45. 4. The invention defined in claim 3, wherein the passageway is defined in part by a groove which is horizontal and straight for part of its length and then curves upwardly, and in part by a pair of spaced fins which are below said groove and are horizontal for part of their length and are curved upwardly for the remainder of their lengths, said fins being exactly alike but being on opposite sides of the passageway and being spaced apart far enough to permit a vertical chain link to pass between them, said fins being spaced from the groove far enough to permit a chain link which is at right angles to the above mentioned vertical link to slide or pass over said fins as the chain moves.
55. 5. The invention defined in claim 3, wherein the cross bore is elongated and is larger than the cross section of the pin, the long axis of the cross bore extending at an angle of about 30° relative to the horizontal.
60. 6. A base member for lift jacks having a socket on its upper face for receiving the lower end of a lift jack thereby to provide a stable support for the lift jack; said base member having a passageway for a link chain extending from one end around in a curve upwardly and adjacent to the socket, said passageway including chain-guiding surfaces; a cross bore intersecting said passageway; a pair of slots provided on the base at the upper end of said passageway; and a chain-locking pin adapted to fit in said cross bore or alternatively in said

slots to lock a pulling chain to the base member, said locking pin being manipulated by the operator to lock or release the pulling chain.

7. A base member for lift jacks having a socket on its upper face for receiving the lower end of a lift jack thereby to provide a stable support for the lift jack; a chain sheave rotatably mounted on the base member to turn in a vertical plane which intersects said socket; a cross bore in the base member intersecting the path of a link chain which may be caused to mesh with said chain sheave; and a chain-locking pin adapted to be inserted in said cross bore.

8. The invention as defined in claim 7, wherein the cross bore is elongated with its long axis directed toward the axis of rotation of the chain sheave and its upper end ending within the pitch circle of the chain sheave.

9. A base member for lift jacks having a socket on its upper face for receiving the lower end of a lift jack

5 thereby to provide a stable support for the lift jack; said base member having a passageway through which a pulling chain may pass; a pair of slots formed on the base member on either side of the passageway adjacent said socket; and a chain-locking pin adapted to lie in said slots transversely to the chain passageway and adapted to contact the chain to prevent movement thereof in one direction through the passageway.
